(57) **CLAIM**

The ornamental design for a windlass clip for a tourniquet, as shown and described.

DESCRIPTION

FIG. 1 is a perspective view of the windlass clip for a tourniquet, showing the new design;

FIG. 2 is a front elevational view of the windlass clip for a tourniquet thereof;

FIG. 3 is a rear elevational view of the windlass clip for a tourniquet thereof;

FIG. 4 is a left side elevational view of the windlass clip for a tourniquet thereof;

FIG. 5 is a right side elevational view of the windlass clip for a tourniquet thereof;

FIG. 6 is a top plan view of the windlass clip for a tourniquet thereof; and,

FIG. 7 is a bottom plan view of the windlass clip for a tourniquet thereof.

In the drawings, the broken lines are for the purpose of illustrating environment only and forms no part of the claimed design.
